STEPHEN W. DOWNEY, OF PIEDMONT, WEST VIRGINIA.

Letters Patent No. 73,881, dated January 23, 1868.

ADDRESS-CASE FOR RAILROAD-CARS.

The Schedule referred to in these Letters Patent and making part of the same.

TO ALL WHOM IT MAY CONCERN:

Be it known that I, STEPHEN W. DOWNEY, of Piedmont, Mineral county, West Virginia, have invented certain new and useful Improvements in Tablet-Frames or Address-Cases for Railroad-Cars and other purposes; and I do hereby declare that the following is a full, clear, and exact description of the same, reference being had to the annexed drawings, and to the letters of reference marked thereon, making part of this specification, and in which—

Figure 1 is a side view of a car, with my improved address-case attached.

Figure 2 is a plan view of my address-case, with the top closed.

Figure 3 is a side and end view.

Figure 4 is a plan view, with the top open.

The nature of my invention consists in securing in a suitable frame, made of cast iron, sheet tin, or other suitable material, a slate or tablet, on which the railroad-station, name, and address of the consignee can readily be placed, and as readily removed after the car has been unloaded. The base of the case, when made of cast iron, is cast with a slate-frame attached, or when of sheet tin, or other like material, the frame is securely attached thereto. This frame is provided with projecting lips or flanges, under which the slate is inserted, and by which it is firmly secured in position, and thus entirely guarded against the danger of being broken or otherwise injured. To the base of the case or slate-frame, as convenience may suggest, I attach a hinged top. This top is simply a metal frame, in which is inserted and secured by suitable means a glass plate, the same being protected by rods or bars. The top can be firmly and securely closed by hasp, staple, and lock, or by a spring-snap, suitably attached to the base of the case.

The object of my invention is to provide a simple and practical means by which railroad companies are enabled, for temporary purposes, to mark the station, names of consignor and consignees, and, if desired, the weight and capacity and number of car, which will entirely supersede the necessity of defacing the car by the continued marking with chalk, as well as do away with the method, which is equally objectionable, of writing the address on a card, and tacking the same to the sides of the car. Both of these methods have long been admitted to be objectionable, for in rainy and stormy weather they are constantly liable, being entirely exposed, to be so defaced as to be rendered unintelligible, and again, by malicious persons they are not unfrequently entirely obliterated or torn off. My tablet-slate is securely guarded against all these objections. It is safely locked in a case, and is there free from the action of the weather, and also securely guarded against all danger of being tampered with by any one not authorized so to do, and at the same time furnish a means whereby the address can be attached with greater facility than by any method now in use; or, if deemed preferable, the address may be written or printed on a card, and placed on the slate, where it will be secured against all danger of being defaced or otherwise injured. Another advantage of my locked case is this: it affords a safe and secure means whereby the manifest can be safely transmitted with the load. The manifest, being placed in the rear of the slate, can be safely transmitted, and with less danger of being lost than when even transmitted with the mail.

To enable others skilled in the art to make and use my invention, I will proceed to describe its construction and operation.

A is the base of the case. To this base I firmly secure a frame, B. When the case is made of cast iron, the frame B is cast in one piece with the frame A, or when it is made of tin, or other sheet metal, it is firmly soldered thereto. This frame B is provided with projecting lips or cleats, b b, under which the slate C is inserted, and by means of which the slate is firmly secured in position. To the base, A, or frame B, I firmly secure, by hinges d d, or other suitable means, the top frame D. Within this frame D, I secure a glass plate, E, which is retained in position by means of cleats, e e, or other suitable means, so arranged that they can readily be raised for the insertion of a new glass should occasion require. To the side of the frame D, I secure a series of rods or plates, e' e', which serve to protect the glass, and guard against the same being broken. a a are metal strips or cleats, attached to or cast with the bottom, A, and by means of which the entire device is firmly secured to the side or end of the car F, at any convenient or desired point. The top frame D can be firmly and securely fastened by means of a hasp, f, clasp, g, and lock, h, the lock being firmly secured to the

frame A by means of a chain, h'; or instead of this method of fastening, a spring-plate, G, may be attached to the frame A, as shown in fig. 2. Within the closed case, at any point that convenience may dictate, I place a suitable receptacle for the sponge i, so arranged as to hold water sufficient to keep the sponge thoroughly moist, and also for the pencil j. The latter may, however, be simply placed loosely within the closed case, where it will be securely held. H is a metal strip, which is firmly secured to the base, A, and is of width sufficient to project a short distance over the entire side of the case. This strip H securely protects the slate and inner portion of the frame from rain, &c., and renders the interior of the case, to all intents and purposes, waterproof. When the case is made of cast iron, the strip or flange H is cast with the base, A.

The operation is as follows: The lock h is unfastened, or when a spring is used the spring G is thrown back, and the top lifted. With the sponge i you can readily obliterate the last address or other memoranda which may be on the slate, and readily transcribe a new address or other item, when the top can be closed and securely fastened, and so remain until the car reaches its destination, which, by means of the glass E, can at any moment be readily ascertained.

The method of attaching the top can readily be changed without interfering in the least with the object of my invention. For instance, the top, instead of being hinged, may be constructed so as to slide in suitable grooves or guides arranged in the slate-frame C, as clearly shown in Figure 5.

Having thus fully described my invention, what I claim therein as new, and desire to secure by Letters Patent of the United States, is—

1. I claim a tablet-case for railroad-cars, constructed substantially as herein shown and described.
2. I claim the slate C and the hinged top D, having a glass, E, when the whole is constructed and arranged substantially as described.

In testimony whereof, I have signed my name to this specification in the presence of two subscribing witnesses.

STEPHEN W. DOWNEY.
